SAFETY LOCK FOR TEXTILE MACHINE COVERS

Joseph Moss, North Smithfield, R. I., assignor to
Whitin Machine Works, Whitinsville, Mass., a
corporation of Massachusetts

Application January 16, 1932, Serial No. 587,136

11 Claims. (Cl. 192—135)

The present invention relates to locks, and more particularly to safety locks for cotton machinery, such as openers and pickers, wherein operating parts such as beaters travel at such 5 high speeds as to be inconspicuous or invisible to the eye.

The main object of the present invention is to provide locking means for cotton machinery to permit convenient opening of the doors or 10 guards of enclosed operating parts when the machine is not running, but positively to prevent access to these parts of the machine when these latter are in operation, and also to prevent starting of the machine when the locking devices are 15 in unlocked relation. A further object of the invention is to provide a single locking device capable of effecting simultaneously the freeing and securing of a plurality of doors or guards.

In the attempt to provide satisfactory safety 20 locks for such doors, covers, and guards, a variety of exacting conditions must be met. The devices must be simple and direct in their action, to make certain that they will work every time. They must be easy to operate, and impose no extra 25 burden or nuisance on the operator, or he will find a way to render them inoperative and subject himself to the hazard they are aimed to protect him from, just to simplify his work. They must not give access to the enclosed parts until the 30 latter have actually come to rest, as serious accidents have happened where the safety locks have been rendered inoperative as soon as the driving power is unshipped, and access thus allowed to the parts while still travelling under 35 their own momentum. They must not rely wholly on magnetism or gravity for their maintenance in a relation to prevent opening of the doors or guards, or on the force of springs with their propensity for failure without warning, or on 40 friction when subjected to the vibration caused by the running of the machine in question or adjoining machines, as is nearly always the case.

With the aim of satisfying these requirements, the invention comprises a wholly mechanical and 45 positive safety lock which not only locks the covers in closed position when the drive-shaft of the dangerous moving parts is in running relation, and correspondingly locks the drive-shaft against rotation before the covers can be raised, 50 as heretofore in certain instances, but also locks the locking device itself in one or other of the positions it assumes in effecting the reciprocal locking and release of these parts, so that it cannot shift or give way accidentally; further, the 55 means adopted for thus locking the locking de-

vice against unintentional shift are provided in duplicate, rendering the possibility of their simultaneous failure practically negligible, and the said means may also be arranged so as to assume their control over the movement of the 5 lock automatically.

Other aims and advantages of the invention are as will appear from the accompanying specification and claims, taken in connection with the drawings illustrating preferred embodiments. 10

In the drawings.—

Fig. 1 is a horizontal sectional view of a cotton cleaner embodying a lock of the present invention.

Fig. 2 is an end elevation of the cleaner.

Fig. 3 is a detail sectional view of the bolt and associated parts.

Fig. 4 is a plan view of certain of the parts of Fig. 3 in disassembled relation.

Fig. 5 is a detail in vertical section, showing 20 an alternative self-actuating form.

The invention is herein illustrated and described as embodied in a cotton beater or cleaner having two doors or covers, and as shown in the drawings comprises a frame 10, having a cleaning 25 chamber enclosed at the top by the cap 11 and provided in the bottom portion thereof with any suitable opening and cleaning instrumentalities, such as grids and perforated plates. A rotor or beater comprising a plurality of spaced discs 14 from which extend radial arms 15 works within the chamber, the discs being fixed on a shaft 16 on which are mounted tight and loose pulleys 18 and 20 respectively. The shaft is driven by a belt which may be shifted from one pulley to the 30 other. 35

The chamber is provided on opposite sides with an inlet 26 and an outlet 28 respectively disposed adjacent opposite ends of the casing. The doors 30 and 32 are provided to permit access to the 40 interior of the cleaner, the former on the inlet side and the latter on the outlet side of the machine. The doors are pivoted on hinges 33, and swing outward and upward in opening. The doors have suitable means (not shown) for holding them tightly closed in air-tight relation when the machine is running. The door 32 lies adjacent to the drive-end frame of the machine, and at the opposite end it terminates short of the end-frame and adjacent to the outlet connection 28; correspondingly, the door 30 does not extend to the end frame of the machine at the drive-end thereof, because of the presence of the inlet 26 adjacent this end, but extends from the 45 50 55

inward lateral face of such inlet clear to the opposite end frame of the machine.

In accordance with the invention, these doors are provided with safety locking means supplemental to and independent of the means for holding them tightly closed. Thus, the door 30 is locked by a long rod 40 which passes through the end frame of the machine, and under the inlet connection 26, with its extremity outside of 10 and overlapping the material of the door, in such relation as to prevent the lifting of the door until the rod is withdrawn a short distance. The door 32 is similarly locked by a short rod 42 which correspondingly overlies the edge of the door to prevent its being raised. The rods 40 and 42 are of 15 such lengths that the doors may be unlocked by sliding the rods slightly toward the drive-end of the machine and to permit such sliding action the rods are fitted loosely through holes in the end 20 frame and the corresponding end portions of the girts 36 extending the length of the machine, the longer of the rods, 40, having an auxiliary guide 37 fixed on the lengthwise vertical flange of the girt 36.

25 To provide for positively maintaining the rods 40 and 42 in locking position, except when the shaft 16 is at rest, the rods 40 and 42 are connected respectively with shift arms 44 and 46. Each arm is securely fastened to its corresponding 30 rod by a pin 48. The arms are connected together by a yoke 50 secured to each arm by a bolt 52. One of the arms, shown as the arm 44, has an integral outwardly projecting cylindrical stop 54, which is adapted to enter between two of the 35 projecting fins 56 formed integrally on the internal face of the tight pulley 18. A number of the fins 56 are provided, spaced only a sufficient distance to permit the entrance of the stop 54 into one of the interstices between adjacent fins 40 when the pulley is at rest, and striking against the rounded end of the stop to prevent its entry if brought against them while the pulley is rotating at speed. The stop 54 is so disposed that it is out of engagement with the fins when the rods 45 are in locking position, but must enter into a position between two adjacent fins before the locking rods are moved sufficiently to unlock the doors.

50 The arms 44 and 46 are moved toward or away from the pulley to withdraw the rods from locking relation with the doors, or return them to such locking relation by two lock-actuating and keeping devices in the form of sliding bolts, both of identical construction. Each bolt comprises a 55 rod 58 slidably movable endwise in bearings 60 on a bracket 62 which has a bottom securing plate 64 attached as by bolts 65 to flanges 66 which extend along the end of the casing and up to the bearing for shaft 16. Each rod 58 passes 60 through an opening 59 in its corresponding shift arm, which latter lies between the bearings 60 of each bracket 62. Upstanding from the bolt rod 58 is a manually operated handle 68 having a 65 knob 70 at the top. The handle is embraced between the main portion of the shift arm and a finger 71 formed integrally on the shift arm, permitting swinging of the handle about the axis of the bolt, but causing bolt and shift arm to move 70 together when the bolt is moved endwise. The shift arms are moved as a unit from locking to unlocking position, or vice versa, by grasping both of the knobs 70 and sliding the bolts endwise. In this manner the lock is operated to withdraw 75 the rods 40 and 42 from the doors and block

the rotation of the beater, or to lock the doors and free the beater for resumed rotation.

5 In order to secure the lock-actuating bolts in one position or the other against vibration or accidental displacement, and thus lock the locking device against unintentional shift, which has resulted in accidents, each bracket 62 has at the top a horizontal shelf 72, formed in the edge with two notches, an inner notch 74 and an outer notch 76, the former to engage the bolt handle 10 68 when in inward or door-locking position, and the latter to engage the handle when in outward or beater-locking position. The handle, when received in one of the notches, is tipped at a considerable angle from the vertical, so that the weight of the knob 70 effectively prevents the bolt from being jarred out of position, and thus from being permitted to move endwise.

15 In Fig. 5 is shown means for making the device self-locking in either the door-locking or beater-locking position, if this additional safeguard is desired. The shank of each handle 20 68 is simply bent away from the beater-shaft 16, so that the center of gravity of the handle and its knob can never be carried into a position vertically above the axis of the bolt 58. Thus except when actively upheld by the operator's hand, the handle will always fall against the shelf 25 72, and hence will automatically enter the notch 74 or 76.

30 It is to be noted that the provision of the lock-actuating and keeping bolts 58 in duplicate doubles the certainty of operation and hence the safety assured by the structure without imposing any material burden on the operator, who simply grasps the two bolt handles simultaneously, one with each hand.

35 Under normal running conditions, the shaft is 40 rotated by the tight pulley, the bolts are retained in their inner positions, and the doors remain locked. If the operator endeavors, through carelessness or otherwise, to open the machine, while the beater is revolving, the rods 40, 42, prevent 45 raising the covers; before the covers can be lifted he must slide the bolts toward unlocking position, but when this is attempted, the rapidly rotating fins 56 on the tight pulley strike the stop 54 in quick succession, thus preventing a complete unlocking movement of the rods, and at the same 50 time make a sufficient noise to warn the operator of his mistake. When the belt is running on the loose pulley, and the rotor has come to a full stop, the operator may easily unlock the doors by disengaging the lock-actuating bolt 55 handles from the inner notches 74 and then sliding the bolts outwardly until the handles move into the outer notches 76, the bolts each carrying its respective shift-arm and rod outward. Since 60 it is necessary for the operator to release and shift both bolts 58 simultaneously, both shift arms are moved together to unlocking position, and there is no possibility of cramping the bolts or the rods in their bearings. The stop 54 enters the space between two adjacent fins and positively prevents accidental starting of the machine while the doors are unlocked. If the stop should strike one of the fins and refuse to enter one of the spaces, the pulley may be turned slightly by hand. After unlocking, either or both doors may be easily opened.

65 Since the stop 54 engages directly with the driving connections, it is impossible to unlock the doors until the machine is completely at rest. Even after the belt is shifted from the tight to 70 the loose pulley, the operator is compelled to 75

wait until the machine slows down, before the doors can be unlocked.

It will be seen that in the preferred form of the invention, only a single stop 54 is employed, controlling the movement of both locking rods 40, 42, making the operation of entering this stop in proper relation between adjacent fins 56 an easy one and simply and quickly performed. A similar stop might be used on the other shift arm, but this is not necessary, because complete protection is afforded by the single stop, nor is it usually desirable, because of the added care and nicety of fitting incident to mounting the parts with sufficient accuracy so that both stops 15 might enter between fins of the pulley. However, if desired for any reason to make provision for locking the doors independently of each other, such a stop would be provided on each shift arm, and the shift-arms allowed to move independently 20 by removal of the yoke 50.

Although the preferred form of the invention has been shown and described herein, it will be understood that the invention is not limited to the arrangements of parts herein specifically disclosed, but may be embodied in various modifications within the scope of the claims.

What I claim as my invention is:

1. In textile machines, the combination with a casing enclosing working parts thereof, and covers or the like removable for access to such parts, of a driving wheel for such working parts having a plurality of interstices, cover-locking means, a stop moving with the cover-locking means to occupy one of the interstices as the covers are unlocked, and a bolt serving both to impart locking and unlocking movement to the locking means and to maintain such locking means in both locked or unlocked relation.

2. In textile machines, the combination with a casing enclosing working parts thereof, and covers or the like removable for access to such parts and a driving wheel for such working parts, of locking means movable parallel to the axis of the driving wheel to lock the latter and free the covers, and conversely to free the wheel and lock the covers, and a member moving with the locking means and locking it in both extreme positions of its movement.

3. In textile machines, the combination with a casing enclosing working parts thereof, and covers or the like removable for access to such parts, and a driving wheel for such parts, of locking devices movable parallel to the axis of the driving wheel to lock the latter and free the covers, and conversely to free the wheel and lock the covers, and a bolt forced to travel with the locking devices and engageable with a fixed part on the casing so as to be locked against movement.

4. In textile machines, the combination with a casing enclosing working parts thereof, and covers or the like removable for access to such parts, and a driving wheel for such parts, of locking devices movable parallel to the axis of the driving wheel to lock the latter and free the covers, and conversely to free the wheel and lock the covers, a bolt forced to travel with the locking devices and having an angularly projecting portion, and notches in connection with a fixed part on the casing to receive such portion to lock the bolt and thus the locking devices against movement.

5. In textile machines, the combination with a casing enclosing working parts thereof, and cov-

ers or the like removable for access to such parts, of a locking rod for each of several covers and located at a point relatively remote from other locking rods, shift arms secured to the locking rods and connected together to compel movement of all the shift arms and locking rods in unison, a driving wheel driving the moving parts having a plurality of projections, and a master stop on one of the shift arms to enter between the projections and prevent rotation of the driving wheel when any and all of the locking rods are withdrawn to permit opening the covers, and conversely to prevent withdrawal of any of the locking rods while the driving wheel is rotating.

6. In textile machines, the combination with a casing enclosing working parts thereof, and covers or the like removable for access to such parts, of a locking rod for each of several covers, shift arms fixed to the locking rods and connected together to move in unison, a driving wheel having a plurality of projections, a stop on one of the shift arms to enter between the projections when the locking rods are withdrawn to permit opening the covers, and means apart from the locking rods locking the shift arms in cover-locking and also in cover-freeing drive-preventing relation.

7. In textile machines, the combination with a casing enclosing working parts thereof, and covers or the like removable for access to such parts, of driving means for the said working parts having a plurality of projections, a locking rod for each of several covers, a shift arm connected to each locking rod, means connecting the shift arms together, a stop in connection with the shift arms to enter between projections of the driving means, and a sliding bolt for simultaneously moving the shift arms.

8. In textile machines, the combination with a casing enclosing working parts thereof, and covers or the like removable for access to such parts, of driving means for the said working parts having a plurality of projections, a locking rod for each of several covers, a shift arm connected to each locking rod, means connecting the shift arms together, a stop on one only of the shift arms, adapted to enter between projections of the driving means when the latter is stationary, a pair of sliding bolts for simultaneously moving the shift arms, a bolt handle and a bracket for each bolt, the bracket having notches to engage the handle in either locked or unlocked position, the handle being inclined when received in one of the notches to retain it in place against vibration.

9. In textile machines, the combination with a casing enclosing working parts thereof, and covers or the like removable for access to such parts, of driving means for the said working parts having a plurality of projections, a sliding locking rod for each of several covers, a shift arm connected to each locking rod, means connecting the shift arms for simultaneous movement, bolt rods passing through the shift arms, a handle connected to each bolt rod, a portion on each shift arm to embrace the handle, and a stop on one of the shift arms to enter between the projections of the driving means when the locking rods are clear of the covers.

10. In textile machines, the combination with a casing enclosing working parts thereof, and covers or the like removable for access to such parts, of driving means for the said working parts hav-

ing a plurality of projections, a sliding locking rod for each of several covers, a shift arm connected to each locking rod, means connecting the shift arms for simultaneous movement, bolt 5 rods passing through the shift arms, a handle connected to each bolt rod, a portion on each shift arm to embrace the handle, a stop on one of the shift arms to enter between the projections of the driving means when the said moving 10 parts are stationary, and a bracket for each bolt having notches to engage the handle.

11. In textile machines, the combination with a casing enclosing working parts thereof, and covers or the like removable for access to such parts, of a movable structure including portions positioned to prevent opening the covers, a guide 5 on the casing, a member travelling with the said structure and relative to such guide, and means for preventing relative movement between this member and the guide.

JOSEPH MOSS. 10
